VEHICLE SIGNAL LIGHT

Joseph Nagy, 1513 Sherwood Court,
Dearborn, Mich. 48124

Filed Nov. 7, 1966, Ser. No. 4,566

Term of patent 14 years

(Cl. D48—32)

FIG. 1

FIG. 2

FIG. 3

FIGURE 1 is a front elevation view of a vehicle signal light embodying my new design.

FIGURE 2 is an enlarged front perspective view of the vehicle signal light.

FIGURE 3 is an enlarged section view of the vehicle signal light taken on plane 3—3 in FIGURE 2.

The broken line showing of the vehicle in FIGURE 1 is for illustrative purposes only.

I claim:

The ornamental design for a vehicle signal light, as shown and described.
